DRUM VALVE AND FAUCET

Walter R. J. Woeck, Auburn, Calif.

Application March 15, 1943, Serial No. 479,280

4 Claims. (Cl. 222—400)

1

This invention relates to a drum valve and faucet especially adapted to use in dispensing liquids from closed containers, such as drums, and it consists in the constructions, arrangements and combinations herein described and claimed.

It is a particular object of the invention to provide a valve in which an automatic control of the vacuum and air pressure conditions within a closed container may be readily controlled and eliminating the need for the usual vent valve ordinarily required in containers of the kind specified, in order that a liquid may be dispensed from the container or drum.

It is also an object of the invention to provide a dispensing valve in which the dispensing faucet or spigot may be fully housed, when in inoperative position, so that it lies substantially flush with the wall of the drum or container, avoiding the possibility of being struck, which eventually might cause a leaky valve.

It is a still further object of the invention to provide a dispensing valve and faucet of simplified construction, of few moving parts, and which may be wholly constructed from plastics.

Additional objects, advantages and features of invention will be apparent from the following description considered in conjunction with the accompanying drawing, wherein.

Figure 1 is a longitudinal sectional view through a valve and faucet constructed in accordance with the invention, in dispensing position.

Figure 2 is a similar view of the device in closed position.

Figure 3 is a front view of the faucet and valve in closed position.

Figure 4 is a longitudinal sectional view of the valve faucet proper.

Figure 5 is a cross section on the line 5—5 of Figure 1.

There is illustrated a dispensing device generally indicated by the reference character 10 consisting of a cylindrical barrel 11 of any suitable diameter and length to meet the particular requirements for a given size of container or drum.

In the present instance we will assume that the dispensing device is to be installed in the bung-hole of a standard drum, a wall 12 of which is indicated in Figures 1 and 2. The barrel 11 is formed with an enlarged body portion 13 at one end having exterior screw threads formed thereon complementary to threads of the bung hole. In order that the barrel 11 may be securely engaged in the bung, a hexagonal or similarly shaped head 14 is formed. The head 14 is

2

formed with a recess 15, concentric with the bore 16 of the cylinder, the recess being interiorly threaded for a purpose to be explained.

The opposite end of the barrel is open and is provided with an annular flange 17 for mounting of a plate 18, now to be described. The plate is in the form of a disk, of the same diameter as the flange 17, suitably apertured to receive machine bolts 19 the latter being threadedly engaged in apertures in the flange 17; a sleeve 20 is arranged on the bolts extended through the apertures of the plate so as to maintain the plate in free sliding relation with the flange, as indicated at 21.

As shown in Figures 1 and 2, the lower side of the barrel 11 is formed with an inlet opening 22, and upon the opposite or upper side a breather port 23 is formed, which is located approximately intermediate the length of the barrel. Upon the bore 16 of the cylinder an inwardly projecting lug 24 is formed which functions for the guidance and retention of a combined valve and faucet, now to be described.

As shown in Figure 4, the valve and faucet is formed as a cylindrical body 25 of a length less than the barrel 11 and of a diameter to snugly yet slidably and rotatably fit within the barrel. The body includes an operating head 26 suitably formed with a hand grip 27 and at the base of the head threads 28 are formed, complementary to the threads 29 of the recess 15.

A longitudinally extending bore 30 is formed in the body of substantial diameter, having a discharge port 31 inwardly of the head 26. At the end opposite the head 26 the bore 30 is closed, substantially by a wall 32, ported as at 33. An inlet port 34 is provided, positioned in the same longitudinal plane and upon the same side of the body as the port 31, the inlet port 34 being aligned with the port 22 of the barrel in the discharging position of the faucet and valve. Diametrically opposite the ports 31 and 34, and air vent 35 is formed opening upon a concentric passage 36 which opens upon the inner end of the body.

The vent 35 is so located that in the discharging position of the faucet and valve, air will be admitted therethrough and through the passage 36 into the interior of the drum.

A breather control plate 37 is mounted upon the wall 32, in the present instance, by means of headed pins 38. The plate 37 is freely mounted upon the pins so that the plate may be moved to control the port 33 and the passage 36.

A pair of longitudinal slots 39 are formed upon the sides of the body 25, located medially there-

of, and in opposed relation. The inner ends of the slots 39 are connected by a concentric slot 40 while the outer ends of the slots 39 are connected by a concentric slot 40'. The slot 40 is positioned on the body 25 so as to lie slightly outward of the port 34 but at the opposite side of the body; while the slot 40' is formed upon the body 25 in opposed relation to the slot 40 and is positioned inwardly of the port 34. At a point opposite the inlet port 34, a slot 41 is formed in the body extending longitudinally from the slot 40 to the end of the body. The slots 39, 40, 40' and 41 are of slightly greater depth and width than the lug 24, so as to readily accommodate the latter, and further should be in such ratio as to permit the threaded portion 28 of the head to engage the threads 29 of the recess 15. The threads should have a pitch so that the head will be fully seated upon a rotation of the body of 180 degrees.

To assemble the faucet-valve in the barrel, the slot 41 is presented to the lug so as to receive the latter, and the body 25 is then moved inwardly of the barrel until the lug engages the concentric slot 40. The faucet-valve is then given a clockwise rotation until the lug engages the end of the slot and a straight inward movement of the faucet-valve will cause the lug to engage in the longitudinal slot 39 and permit reciprocatory movements of the faucet-valve as will be required.

The discharging position of the faucet is shown in Figure 1 and in normal operation liquid will pass through the aligned ports 22, 34, the bore 30 to the discharge outlet 31. The degree of discharge of liquid may be regulated by the location of the port 34 with respect to the port 22. The closed position of the faucet-valve is shown in Figure 2, wherein the valve body has been rotated 180 degrees so as to present the discharge port 31 at an uppermost position with the ports 22 and 34 out of alignment. It will also be seen that the threads 28 and 29 are engaged to maintain the body in such position against accidental opening of the valve. Inasmuch as the body is rotated only 180 degrees, it is necessary that the pitch of the threads 28 and 29 be such as to permit full seating of the head 26 within the recess 15. When it is desired to move the valve from a discharging position (Figure 1) to a closed position (Figure 2), the body member 25 is moved inwardly, the lug 24 guiding the body in its longitudinal path until it reaches the concentric slot 40'. At this time, the threads 28 are in position to engage the threads 29, and by rotating the body by means of the head 26 through 180 degrees, which is permitted by reason of the fact that the lug 24 is now in alignment with the slot 40', the head 26 will be fully engaged in the recess 15.

During discharge position of the valve (Figure 1), air is admitted by way of the vent 35 and passage 36 into the interior of the drum by way of the breather port 23 or through the space 21.

In the event that an unusual pressure or vacuum condition is required within the drum, the valve is withdrawn to discharge position and then rotated counterclockwise 180 degrees so as to present the arrow 42 to the pressure indication point 43. The port 34 is thus moved to a closed position and rotation of the valve will have aligned the lug 24 with a slot 39 on the opposite side of the body 25. The valve-faucet may now be reciprocated inwardly and outwardly. On the inward stroke the plate 37 will close the port 33

and passage 36, creating a pressure on liquid in the space 44 of the barrel. On the outward stroke, the plate 37 will be unseated and air is admitted to the chamber 44 by way of the vent 35 and passage 36, air also passing through port 33 into the chamber 44, from whence air may pass into the drum by way of the port 23. Passage of air in this manner obviates the need for special vent valves in the drum to insure proper flow of liquid through the faucet. The operation may be continued until the required pressure has been attained, which will vary, depending upon the viscosity of the liquids to be dispensed.

While a preferred construction of the valve-faucet has been shown and described, this is by way of illustration only, and I consider as my own all such modifications in construction as fairly fall within the scope of the appended claims.

20 I claim:

1. A dispensing device for closed containers consisting of a barrel adapted to be threadedly engaged in a bung hole of a container, the barrel having a valve at its inner end and an inlet port, a cylindrical valve and faucet reciprocable within the barrel and having a longitudinal passage stopping short of the inner end, an inlet port being formed in the valve and faucet forming communication between the passage and the first named inlet port, the outer end of said cylindrical valve and faucet having a discharge port in communication with the longitudinal passage, means for limiting outward movement of the cylindrical valve and faucet, said cylindrical valve and faucet having an air vent forming communication between the atmosphere and the interior of a container when partially withdrawn from the barrel, the cylindrical valve and faucet having a valve at its inner end for closing said air vent upon inward movement thereof, said cylindrical valve and faucet being rotatable to close the first named inlet port and reciprocable to build up pressure in the closed container.

2. A dispensing device for closed containers consisting of a barrel adapted to be threadedly engaged in a bung hole of a container, the barrel having an open inner end and an inlet port, a lug on the interior of the barrel, a cylindrical valve and faucet within the barrel having a pair of longitudinally spaced concentric slots arranged upon opposite sides of the valve and faucet and extending partially therearound, the terminal ends of said slots on each side being connected by a longitudinally extended slot, said lug being adapted to traverse the longitudinal slot during reciprocation of the cylindrical valve and faucet and the concentric slots under rotation of said valve and faucet when aligned therewith, a third longitudinal slot being formed in the cylindrical valve and faucet extending from the innermost concentric slot to the end of said member for initial engagement of the lug, said cylindrical valve and faucet having a longitudinal passage stopping short of the inner end and having a port formed therein, an inlet being formed in the cylindrical valve and faucet forming communication between the passage and the first named inlet port in one position of the cylindrical valve and faucet, the outer end of said cylindrical valve and faucet having a discharge port in communication with the longitudinal passage, said outermost concentric slot and lug forming means for limiting outward movement of the cylindrical valve and faucet, an air vent formed in the cylindrical valve and faucet establishing

communication between the atmosphere and the interior of a container when partially withdrawn from the barrel, a flap valve controlling the open end of the barrel, a flap valve controlling the port of the cylindrical valve and faucet, said barrel having a breather port positioned to establish communication between the container and the barrel on full extended position of the cylindrical valve and faucet, said barrel having a recess exterior of the container interiorly threaded, and said cylindrical valve and faucet being provided with threads engageable with the threads of the recess upon inward movement and partial rotation of the cylindrical valve and faucet.

3. The structure of claim 1, in which the valve 15

of the cylindrical valve and faucet consists of a port formed in the inner end thereof, a plate member mounted on the interior end of the cylindrical valve and faucet movable rearwardly to close said air vent and said last named port upon inward movement of the cylindrical valve and faucet.

4. The structure of claim 1, in which said barrel member is formed with an open end and the valve therefor consisting of a plate member mounted on the interior end of said barrel member and movable to close said open end upon outward movement of the cylindrical valve and faucet.
